UNITED STATES PATENT OFFICE.

EDWIN B. STIMPSON, JR., OF BROOKLYN, NEW YORK.

DESIGN FOR TRIMMING.

SPECIFICATION forming part of Design No. 18,770, dated November 27, 1888.

Application filed October 1, 1888. Serial No. 286,892. Term of patent 3½ years.

To all whom it may concern:

Be it known that I, EDWIN B. STIMPSON, Jr., of the city of Brooklyn, in the county of Kings and State of New York, have invented and produced a new and original Design for Trimmings, of which the following is a specification.

My design is especially intended for trimmings made of leather.

10 I will describe my design in detail, and then point out the novel features in the claim.

The accompanying drawing illustrates my design.

15 The design consists, essentially, of two sinuous rows of circles, which rows extend in such

manner that their curves intersect each other to form elliptical figures A. Outside the rows of elliptical figures I have shown scallops a, of alternate angular and curved outline, whereby points and semicircles are formed. 20

What I claim as my design is—

A design for trimmings, comprising two sinuous rows of circles, which rows intersect each other so as to form elliptical figures, and scallops outside said sinuous rows, substantially 25 as shown.

EDWIN B. STIMPSON, JR.
